RECESSED ELECTRIC LIGHTING CEILING
FIXTURE SUPPORT AND PLASTER FRAMEBertram A. Kaeppele, Normandy, Mo., assignor to
Day-Brite Lighting, Inc., St. Louis, Mo., a cor-
poration of Missouri

Application November 8, 1946, Serial No. 708,545

7 Claims. (Cl. 240—78)

1

This invention relates to supporting and plaster frames for flush-type electric lighting ceiling fixtures. The invention has for its principal objects a strong and rigid, simple and economical light-weight frame of the above type which can be quickly and easily assembled from stock parts to accommodate single or multiple unit fixtures of different length, width and/or depth, which will provide adequate support for the fixture and which will define the fixture receiving opening in a plaster ceiling. The invention consists in the electric lighting ceiling fixture support and plaster frame and in the parts and combinations and arrangements of parts hereinafter described and claimed.

In the accompanying drawings, which form part of this specification and wherein like symbols refer to like parts wherever they occur,

Fig. 1 is a top plan view, showing my electric lighting fixture support and plaster frame embodied in a suspended plaster ceiling,

Fig. 2 is a side elevational view of said frame, with portions of the plaster ceiling at the ends thereof shown in the vertical section,

Fig. 3 is an enlarged transverse sectional view on the line 3—3 in Fig. 2,

Fig. 4 is a fragmentary central longitudinal view on the line 4—4 in Fig. 3,

Fig. 5 is an enlarged fragmentary top plan view of one of the corner portions of the frame,

Fig. 6 is a vertical longitudinal sectional view on the line 6—6 in Fig. 5,

Fig. 7 is an enlarged fragmentary top plan view of one of the side rails of the frame at the joint between the endwise abutting sections thereof,

Fig. 8 is an inner side elevational view of the parts shown in Fig. 7,

Fig. 9 is a perspective view of one of the side rail sections and one of the angle corner coupling plates,

Fig. 10 is a fragmentary vertical cross-sectional view showing a modified arrangement for securing the fixture housing to the frame; and

Fig. 11 is a fragmentary horizontal section on the line 11—11 in Fig. 10.

In the accompanying drawings, my electric lighting fixture support and plaster frame is shown embodied in a suspended plaster ceiling 1 which is applied to the underside of metal lathing 2 that is laced to the undersides of spaced horizontal channels 3 which, in turn, are suspended from a floor or roof (not shown). The frame is supported on the channels 3 and defines the fixture receiving opening in the

2

plaster ceiling 1 which is laid up against said frame around the four sides thereof flush with the lower edge thereof. The frame illustrated in the accompanying drawings is adapted to accommodate two elongated fluorescent lighting fixture housings 4 that are disposed in endwise abutting relation.

Each side of said frame is formed by two counterpart sheet metal side rail sections A disposed in endwise abutting relation, and the ends of the frame are made of single counterpart sheet metal end rail sections B. Each of the side and end rail sections A and B has hollow top and bottom marginal beads 5 along the inner side of the upright wall thereof and a single hollow longitudinal medial rib 6 along the outer side that has a narrowed entrance or beaded lip portion 7 on the inner side of said section. The hollow outstanding ribs 6 of the side rail sections A extend from end to end thereof, while the corresponding ribs of the end rail sections B terminate short of the ends thereof. The end rail sections B have the portions thereof located beyond the ends of their hollow ribs 6 bent at right angles and disposed in endwise abutting relation to the adjacent ends of the side rail sections B.

The side and end rail sections A and B are connected together at each corner of the frame by means of an angular coupling plate 8 having one leg extending into the hollow rib of a side rail section and the other leg extending into the hollow rib of an end rail section. Each corner coupling plate 8 may be permanently secured in the hollow rib of an end rail section B by a rivet 9 and in the hollow rib of a side rail section A by a bolt 10. The abutting ends of the side rail sections A are secured together by means of coupling or splice plates 11 which extend into the hollow ribs 6 of said sections and are secured therein by bolts 12. The ends of the coupling plates 8 and 11 are beveled so as to facilitate entry thereof into the ends of the hollow rib 6.

The fixture housings 4 are supported in the frame by means of substantially inverted U or bail-shaped suspension straps 13 of channel shaped cross-section. The suspension straps 13 span the frame from side to side thereof with their depending end portions seated on the outstanding hollow ribs 6 of the side rail sections A and secured to the vertical portions thereof by means of screws 14. The suspension straps 13 have threaded studs 15 depending from the tops thereof that extend downwardly through the

3

tops of the fixture housings 4 and are provided with thumb or wing nuts 16 for suspending said housings from said studs. The suspension straps 13 may be made in different heights for fixture housings of different depths.

In the arrangement shown in the drawings, the outstanding hollow ribs 6 of the frame seat on the supporting channels 3 adjacent thereto, two of said channels extending lengthwise of the end rail sections B below the outstanding ribs thereof and the channels between said end rail supporting channels being disposed in endwise abutting relation to the outer side faces of the side rail sections A beneath the outstanding ribs thereof. As shown in the drawings, the frame is secured to the plaster ceiling supporting channels 3 by lacing wires or ties 17 that extend through registering vertical holes in the channels and in the hollow outstanding ribs 6 of the side and end rail sections A and B of said frame. During the operation of applying the plaster ceiling 1 around the frame flush with the beaded lower edge 5 thereof, the side rails A of said frame are held in proper spaced relation by means of cross members 19 having down-turned end flanges that fit in vertical openings formed in said side rail sections by portions 20 thereof that are pressed inwardly between pairs of horizontal slits therein.

In the modified construction shown in Figs. 10 and 11, the fixture housing 4^a supporting straps 13 are dispensed with and the housing is supported in the frame by means of metal plates 21 that are formed at one end with angularly bent flanges 22 and intermediate their ends with prongs 23 that are struck up at the side edges of said plates. With this arrangement, the clips or plates 21 are inserted in openings 24 provided therefor in the side walls of the fixture housing 4^a and their prongs 23 are forced into the hollow ribs 6 of the rail sections through the narrow beaded lip portions 7 thereof, thus firmly anchoring said clips within said ribs.

The hereinbefore described fixture supporting and plaster frame has numerous advantages. It may be readily assembled from different lengths of side and end rail sections to form a frame of a width and length that will accommodate single or multiple fixtures of different lengths and widths, and suspension straps of different vertical dimensions may be used for fixture housings of different depths. The frame is strong and durable and light in weight and serves as a protecting lining for the fixture receiving opening in the plaster ceiling and as a form for said opening during the plastering operation. The cross ties and struts serve to prevent the side rails of the frame from spreading or collapsing inwardly during the operation of forming the plaster ceiling around said frame and may be easily removed after the plaster has set. The fixture housings may be quickly and easily attached to the frame; and the rail sections of the frame may be quickly and easily secured together along the sides of the frame and at the corners thereof by the means of the straight and angle coupling members.

Obviously, the hereinbefore described combination fixture support and plaster frame admits of considerable modification without departing from the invention. Therefore, I do not wish to be limited to the precise construction shown and described.

What I claim is:

1. A unit handled electric lighting fixture supporting and plaster frame assembly for a sus-

4

pended plaster ceiling comprising separate sheet metal side and end sections with upright walls having outstanding hollow longitudinal ribs along the outer sides thereof adapted to seat on suspension elements for said plaster ceiling, and separate coupling members having angularly disposed end portions extending within and secured to adjacent ends of the hollow ribs of said side and end sections at the corners of said frame.

5 2. A unit handled electric lighting fixture supporting and plaster frame assembly for a suspended plaster ceiling comprising separate sheet metal side and end sections with upright walls having outstanding hollow longitudinal ribs along

10 the outer sides thereof adapted to seat on suspension elements for said plaster ceiling, separate coupling members having angularly disposed end portions extending within and secured to adjacent ends of the hollow ribs of said side and end sections at the corners of said frame.

15 20 3. A unit handled electric lighting fixture supporting and plaster frame assembly for a suspended plaster ceiling comprising separate sheet metal side and end sections with upright walls having outstanding hollow longitudinal ribs along

25 the outer sides thereof adapted to seat on suspension elements for said plaster ceiling, separate coupling members having angularly disposed end portions extending within and secured to adjacent ends of the hollow ribs of said side and end sections at the corners of said frame, said side sections having openings in the inner sides thereof adapted to temporarily receive and support tie and strut members for holding said side sections in proper spaced relation during the operation of

30 applying the plaster ceiling around said frames.

35 4. A unit handled electric lighting fixture supporting and plaster frame assembly for a suspended plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame.

40 5. A unit handled electric lighting fixture supporting and plaster frame assembly for a plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame, said side sections having openings in the inner sides thereof adapted to temporarily receive and support tie and strut members for holding said side sections in proper spaced relation during the operation of

45 30 applying the plaster ceiling around said frames.

35 6. A unit handled electric lighting fixture supporting and plaster frame assembly for a suspended plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame.

40 7. A unit handled electric lighting fixture supporting and plaster frame assembly for a plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame, and an inverted U-shaped strap spanning from side to side of said frame and rigidly secured thereto for supporting an electric lighting fixture therein.

45 8. A unit handled electric lighting fixture supporting and plaster frame assembly for a suspended plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame, and an inverted U-shaped strap spanning from side to side of said frame and rigidly secured thereto for supporting an electric lighting fixture therein.

50 9. A unit handled electric lighting fixture supporting and plaster frame assembly for a plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame, and an inverted U-shaped strap spanning from side to side of said frame and rigidly secured thereto for supporting an electric lighting fixture therein.

55 10. A unit handled electric lighting fixture supporting and plaster frame assembly for a suspended plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame, and an inverted U-shaped strap spanning from side to side of said frame and rigidly secured thereto for supporting an electric lighting fixture therein.

60 11. A unit handled electric lighting fixture supporting and plaster frame assembly for a plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame, and an inverted U-shaped strap spanning from side to side of said frame and rigidly secured thereto for supporting an electric lighting fixture therein.

65 12. A unit handled electric lighting fixture supporting and plaster frame assembly for a suspended plaster ceiling comprising separate sheet metal side and end sections with upright walls having outstanding hollow longitudinal ribs along the outer sides thereof, separate coupling members having angularly disposed end portions extending within and secured to adjacent ends of the hollow ribs of said side and end sections at the corners of said frame, and an inverted U-shaped strap spanning from side to side of said frame and rigidly secured thereto for supporting an electric lighting fixture therein.

70 13. A unit handled electric lighting fixture supporting and plaster frame assembly for a plaster ceiling comprising separate sheet metal side and end sections having outstanding hollow longitudinal ribs along the outer side faces thereof, and separate angle coupling members extending within and secured to adjacent ends of said hollow ribs of said side and end sections at the corners of said frame, the hollow ribs of some of said

sections having entrance openings on the inner sides thereof, and fixture supports insertable in said grooves through the entrance openings thereof.

7. An electric lighting fixture supporting and plaster frame for a plaster ceiling comprising separate side and end sections having outstanding hollow longitudinal ribs along the outer sides thereof, separate coupling members extending within and secured to adjacent ends of said hollow ribs of said side and end sections at the corners of said frame, the hollow ribs of some of said sections having narrowed entrances through the inner side faces thereof, and plates insertable in said grooves through the narrowed entrances thereof, said plates having thickened portions adapted for forceful entry into said ribs through

the narrowed entrances thereof and portions located inside said frame for supporting an electric lighting fixture therein.
